(57) **CLAIM**

We claim an ornamental design for a transcranial magnetic stimulation system, as shown, and described.

DESCRIPTION

FIG. 1 is a right perspective view of a transcranial magnetic stimulation system in accordance with the design;

FIG. 2 is a left perspective view of the transcranial magnetic stimulation system of the design that is depicted in FIG. 1;

FIG. 3 is a right side view of the transcranial magnetic stimulation system of the design that is depicted in FIGS. 1-2;

FIG. 4 is a left side view of the transcranial magnetic stimulation system of the design that is depicted in FIGS. 1-3;

FIG. 5 is a top view of the transcranial magnetic stimulation system of the design that is depicted in FIGS. 1-4; and,

FIG. 6 is a front view of the transcranial magnetic stimulation system of the design that is depicted in FIGS. 1-5.

The dashed lines are shown in the views for illustrative purposes only and form no part of the claimed design.
